UNITED STATES PATENT OFFICE.

ROBERT E. CARMICHAEL, OF DAMON, TEXAS.

ROTARY BORING-DRILL.

1,295,969.

Specification of Letters Patent.

Patented Mar. 4, 1919.

Application filed November 18, 1918. Serial No. 262,963.

To all whom it may concern:

Be it known that I, ROBERT E. CARMICHAEL, a citizen of the United States, residing at Damon, Brazoria county, Texas, have invented a certain new and useful Improvement in Rotary Boring-Drills, of which the following is a full, clear, and exact description, such as will enable others skilled in the art to which it appertains to make and use the same.

My invention relates to rotary boring drills for use in drilling oil, water or gas wells or in mining in earth or rock. It is especially adapted for use in soft formations such as clay, gumbo, sand or shale but may also be used in hard formations.

An object of my invention is to provide a drill bit which will drill a hole of such size that a well casing may be driven down after the drill, but in which the bit is collapsible in such manner that it may be withdrawn from the well when necessary for sharpening or adjustment, without removing the casing also.

Another object of my invention is to provide a drill bit of the character described which will be simple and rugged in structure and which will not clog in such manner that it will not collapse when it is attempted to withdraw the tool from the well.

In the accompanying drawing forming a part of this specification I have illustrated the preferred embodiment of my invention although it is obvious that various changes and modifications might be made thereto without departing from the spirit of my invention.

Referring to the different views wherein like characters of reference are applied to like parts throughout: Figure 1 is a central longitudinal section of my improved drill the blades of the drill being shown in elevation. Fig. 2 is a transverse section on the line 2—2 of Fig. 1. Fig. 3 is a central longitudinal section similar to Fig. 1, but showing the blades of the bit collapsed. Fig. 4 is a view similar to Fig. 1, but taken at right angles to the position shown in that figure. Fig. 5 is a transverse section taken on line 5—5 of Fig. 4. Figs. 6 and 7 are views of one of the drill blades detached and Fig. 8 is a view on a reduced scale showing the upper end of the drill stem and casing and illustrating the means by which the flushing water finds an

inlet into the pipes while the drill is in operation. Figs. 9 and 10 are longitudinal and transverse views, respectively, illustrating the use of my registering means for the bit.

In the use of my improved collapsible drill I contemplate applying the power from the rotary to an outer casing 6, which is adapted to cause the rotation of an inner drill stem 7, having attached to the lower end thereof a collapsible bit 9 of the fish tail type now in common use in drilling in soft formations. The manner in which rotation is imparted to the drill stem and the drill attached thereto will more clearly appear in the description which follows. At the lower end of the drill stem 7, I have provided a specially constructed drill collar 8, having an interiorly threaded shank 9 for attachment to the drill stem. The drill collar is cylindrical at the upper shank 9, but is dish or bowl-shaped at a point intermediate its ends and is provided at the lower end with a threaded seat 10 into which is threaded a split ring 11 adapted to form an attaching means for the upper arms 12 of the cutting blades and also to form a conical seat for the upper tapered shank 13 of the bit. This ring 11, as shown particularly in Fig. 5, is split into two parts, which when properly registered in position, are adapted to be threaded into the seat 10 at the lower end of the drill collar. In order to prevent the ring 11 from becoming unscrewed and loosened from the drill collar, I have provided two set screws 14, one at each side of the said ring, said screws being threaded to fit partly in the drill collar and partly in the ring at the point where they are threaded together, in such manner as to prevent rotation of the ring while the set screws are in position.

The bit 9 is made up of two blades adapted to fit together on the inner face thereof, said blades each being provided with a thickened shank 14 tapered at 13 as previously described. The two blades of the bit 9 are adapted to collapse after the manner of the blades in a pair of shears. When so collapsed they will assume the position shown in Fig. 3. In order to allow for the blades to assume the closed position thus shown, it is necessary that a part of the tapered upper shank be cut away on each side to allow for a lateral movement of the parts from the expanded position shown in Figs. 1 and 4 to the closed

position shown in Fig. 3. For this purpose a part of the shank as shown at 15, on each blade is cut away along a curved and somewhat irregular line to allow movement of the 5 blades into the collapsible position. It is obvious that when thus collapsed the parts of the shank on each of the blades thus cut away will contact with each other in such manner as to prevent further movement of 10 the blades toward each other, and when in this position the blades will be sufficiently reduced in width to fit within the outer casing 6 in such manner that they may be moved vertically within the casing.

15 With special reference to Fig. 3, it will be seen that when in collapsed position the upper arms 12 of the blades are still recurved in such manner that on the elevation of the drill stem the upper surface of the ring 11 20 will receive the arms 12 and prevent the detaching of the bit from the drill collar.

In order to hold the blades in collapsed position while the bit is being inserted into or removed from the well, I use a locking 25 ring 16, having an upper thickened portion 17. This ring is a such size as to fit loosely within the outer casing and to inclose the blades of the bit in such manner that the thickened portion 17 will hang upon the upper 30 portion of the blades and hold the blades tightly together with the shoulders adjacent the cutaway portion 15 in close contact with each other.

For the purpose of removing the ring 16 35 from the blades at the proper point within the casing, I have provided two opposite flanges 18 on the inner side of the casing which project out into the interior thereof a distance sufficient to receive the ring 16 and 40 prevent further movement downward thereof. The outer casing is also provided at the lower end thereof with two slots 19 approximately opposite each other, but slightly staggered, in order to receive the blades of 45 the bit 9 when the same are expanded into operating position. Slightly above the slot 19 and below the two flanges 18, I have provided two inwardly projecting supports or flanges 20. These two supports project inwardly 50 from the sides of the casing at a point on the inner periphery of the said casing at right angles to the position of the flanges 18 previously described and at right angles to the flat side of the cutting blades 55 of the bit 9. These flanges are slightly inclined from the horizontal, one of these being inclined downwardly in one direction and the other in the opposite direction. This inclination is for the purpose of receiving 60 the lower inclined shoulders 21 of the blades.

With reference to Fig. 5, it will be noted that the two supports 20 are slightly staggered relative to each other in such manner

as to more conveniently receive the shoulders 65 21 on the lower face of the shank 14 of the bit.

The casing 6 and the drill stem 7 are rotated by the means ordinarily used in rotary drilling rigs. The casing 6 projects upwardly from the derrick platform and is received in a rotary not shown. The rotary motion is thus imparted to the casing 6. The bit, the casing, and the drill stem are supported at the upper end by the usual 70 bail 22, supported from the upper part of the derrick by the usual block and tackle not here shown, as forming no part of this invention. The casing has at its upper end an enlarged coupling or swage 23, threaded 75 interiorly at its upper end to a length of pipe 24. This pipe is perforated at a point intermediate its ends as shown at 25, and said perforated portion is inclosed by a swivel connection 26, fitting tightly at both 80 ends around the said casing by means of stuffing boxes 27 and having a threaded attaching nipple 28 through which flushing water may be pumped downwardly inside the casing. The said swivel is supported 85 rotatably upon the casing extension 24 by means of a supporting ring 29. Immediately above the swivel 26 is attached the bail 22, said bail being attached to the supporting block 30, within which the casing extension 24 is adapted to rotate and to be supported by means of a rotary block 31 between which and the supporting block 30 are provided the usual non-friction rollers 32. The upper end of the casing extension 100 24 is adapted to fit rotatably around the drill stem 7 and to make a fluid tight connection therewith by means of the stuffing box 33.

The upper end of the drill stem 7 is provided with a laterally extending flange 34 and fits fluid tight within the swivel 35, said fluid tight joint being made by means of the stuffing box 36 beneath the radial flange 34. The swivel 35 has attached to the upper end 105 thereof the goose-neck 37 to which may be attached a flexible hose leading to a water supply.

In Figs. 9 and 10 I have shown a means of so turning the bit, as it is lowered into the 115 end of the well, that the blades thereof will be in proper position to expand outwardly through the slots 19 in the casing. The inner sides of the casing above the supports 20 are provided with spiral flanges 40. 120 These flanges project inwardly sufficiently to receive the outer edges of the collapsed blades of the bit 9. If the blades are not in proper position to register between the supports 20 and expand through the slots 19 125 they will be given a twisting or rotating movement by contact with the flanges 40 so as to place them in the proper position as

they are lowered. When this registering flange 40 is used no flanges 18 will be necessary as will be obvious. The flange 40 will serve to remove the ring 16 when same contacts with the upper edge thereof.

The operation of my device may now be understood. When it is desired to insert the bit 9 into a casing 6 within a well the bit is collapsed into the position shown in Fig. 3. The split ring 11 is unscrewed from the lower end of the drill collar 8 and in the collapsed position the upper arms 12 of the bit are introduced into the drill collar. The two parts of the split ring 11 are then fitted around the upper end of the shank 14 of the bit and registered in such position that they may be threaded within the lower end of the drill collar. When thus screwed in place, the set screws 14' are introduced, thus fixing the ring 11 against removal. The ring 16 is then dropped down over the blades of the bit holding them collapsed with the shoulders adjacent the cut-away section 15 in close contact with each other, the bit is then inserted into the casing. When the ring 16 comes in contact with the flanges 18 on the interior part of the casing the ring 16 will be stopped and the blades released.

If the registering flange 40 is used no flange 18 will be necessary. The blades of the bit will be diverted by the spiral turn in said flange 40 and turned into proper position to adapt the blades to expand through slots 19 in the casing. When the shoulders 21 on the outer side of each of the blades come in contact with the supports 20 on the inside of the casing the lower point on said beveled shoulder will strike the supports 20 first and will thus bring the bit to a stop. The inner point of the ring 11 which forms a conical seat for the tapered shank 13 of the bit will contact with the upper part of said tapered portion, as shown in Fig. 3, thus acting to push the upper part of the blades toward each other and to shove the outer portion of the blades outwardly through the slots 19 of the casing. It will be noted that the shank 14 of the bit will be clamped between the lower end of the drill collar and the two supporting flanges 20 in such manner that the blades will act to expand in an obvious manner and to assume the position shown in Fig. 1. When expanded to their full operative position the shoulders 21 of the shank will rest closely upon the inclined supporting flanges 20 of the casing. The weight of the drill stem bearing down upon the shank of the bit will hold the blades firmly in position and prevent any lateral movement thereof.

Flushing water is pumped downwardly into the well from the surface for the pur-

pose of washing away the material disintegrated by the rotation of the bit and such material will find a passage upwardly outside of the casing 6 to the surface. The blades of the bit 9 are adapted to drill a hole of sufficient diameter that the casing 70 may easily follow the bit and space be allowed outside of the said casing for the upward passage of the water. The water pumped into the drill stem finds an entrance through the goose neck 37 and the 75 swivel 35 to the rotating drill stem 6 and passes downwardly through the drill stem to the upper shank of the bit. Water passages 38 are provided through the shank 14 of the bit on the sides adjacent the flat portions of the blades, thus opening downwardly into contact with the material being loosened by the said blades. Water is also pumped downwardly inside the casing and between the same and the drill stem. This 85 water finds entrance into the rotating casing through the nipple 28 in the swivel connection 26 at the upper end of said casing. From there it passes downwardly and issues into the bottom of the well by means of lateral perforations 39, said perforations being formed immediately adjacent the shank of the bit. It is obvious that a certain amount of this water will also issue directly downward around the sides of the blades of the 95 bit 9. A large supply of flushing water is thus obtained, sufficient to keep the blades of the bit clear of disintegrated matter at all times.

When it is desired to withdraw the bit 100 from the casing for the purpose of sharpening same or replacing broken parts the drill stem will be hoisted at the surface, by means of a block and tackle secured immediately below the swivel 35, the drill stem being 105 adapted to telescope within the casing and within the upper stuffing box 33 thereof. As the drill collar 8 is drawn upwardly the lower end thereof will contact with the arms 12 of the blades serving to draw them together, thus also contracting the blades 21 and to withdraw them from the slots 19 in the lower end of the casing. The outer shoulders of the blades, as the same are being drawn upwardly will catch upon the 110 flange 17 of the locking ring 16 thus serving to hold the said blades in contracted position until the surface is reached. It is obvious that the supporting flanges 18 may be dispensed with if desired, as the supporting flanges 20 will receive the said ring in sufficient time to release the blades before they are expanded. I prefer however, to release the blades at a point slightly above the supporting flanges 20, in order that they 115 may be properly loosened before the slots 19 in the side of the casing are reached.

The advantages of my improved drill lie

in the simplicity of construction by means of which there are no parts to be broken or to get out of order. No springs or other delicate mechanism are necessary in the use 5 of my invention. There is a positive expansion of the blades and equally positive action in contracting the same. The clamping of the shanks 14 between the drill collar and the supporting flanges 20 of the casing 10 will serve to drive the blades firmly outward. When the drill stem is raised the upward arms 12 thereof are drawn together and as the bit is raised the outer shoulders of the blades are drawn in by the beveled upper 15 portion of the slot 19, thus serving also to contract the blades with an equally positive action. This type of bit is especially useful in boring in formations such as loose sand or heaving shale where it is necessary to 20 leave the casing in the well in order to properly support the weight thereof when the bit is withdrawn. When the surface formation has been entirely penetrated and the rock has been reached it may then be 25 necessary to withdraw my collapsible bit and use in place thereof a rock bit of different type. If such is the case a reamer is introduced into the casing after the bit has been withdrawn and the supporting flanges 30 18 and 20 are reamed away from the sides of the casing. A rock bit with a diameter the same as the inner part of the casing is lowered into the well and the drilling of the well may then proceed through the rock 35 without the necessity of following the bit with the casing, it being obvious that the danger of the caving in of the sides of the well no longer exists in the harder rock.

Having thus described my invention, the 40 objects and advantages of which will be obvious without further description what I claim as new and desire to protect by Letters Patent is:

1. In a collapsible bit for drilling, an outer 45 casing the lower end thereof having slots therein, a supporting flange above said slots, an inner drill stem, collapsible cutting blades on said drill stem, a conical seat on the lower end of said drill stem, a conical shank on 50 said blades adapted to fit in said seat, a lower inclined base on said conical shank adapted to seat upon said supporting flange and to assist in expanding said blades.

2. In a drill of the character described, a 55 drill stem, a drill collar thereon, a split ring threaded on said collar forming a conical seat, a pair of cutting blades in said collar, a conical shank on the upper part of said blades adapted to fit in said seat, curved 60 arms on said blades above said ring, a casing outside said drill stem and a support for said bit on said casing.

3. In a device of the character described 65 a drill stem, a drill thereon comprising two

collapsible blades, said blades fitting together and having an upper conical shank, a conical seat on said drill stem, a lower shoulder on said shank, a casing outside said drill stem and a supporting flange thereon adapted to receive said shoulder to support 70 said bit and to assist in expanding said blades.

4. In a device of the character described, a drill stem, a casing, a drill collar on said drill stem, collapsible cutting blades in said 75 collar, a beveled shank on said blades adapted to fit in a seat in said collar when said blades are in expanded position, arms on said blades adapted to support said blades in said collar when in collapsed position, and flanges 80 on said casing to support said bit and assist in expanding said blades.

5. In a device of the character described a drill stem, a casing, a drill collar on said drill 85 stem, a supporting flange on said casing, collapsible cutting blades, a ring to hold said blades collapsed, means on said casing to remove said ring, means on said drill collar co-operating with said supporting flange to expand said blades and means on said cas- 90 ing to rotate said blades.

6. In a device of the character described, a drill stem, a casing outside said drill stem, a collapsible drill on said drill stem, means on said drill stem to expand said drill, means 95 on said casing to support said drill and to co-operate with said drill stem in expanding the drill, means to direct the flushing water through the drill and through said casing.

7. In a device of the character described, a 100 drill stem, a drill collar thereon, a split ring threaded therein, a set of expanding cutters, means on said cutters to hold said cutters in said ring, means on said blades to prevent their contraction beyond the desired point, a 105 casing outside said drill stem, means on said casing co-operating with said ring to expand said cutters.

8. In an expanding drill bit, a pair of 110 cutting blades, a tapered shank thereon, arms on said blades to support said bit in the drill stem and to assist in collapsing the blades, a beveled shoulder on said shank to assist in expanding said blades, and a flange on said casing to support said bit in opera- 115 tive position.

9. In a rotary drill, a casing, supporting flanges thereon, a drill stem, a set of cutting blades thereon, arms on said blades to sup- 120 port said blades in said drill stem, a tapered shank on said blades, and a beveled shoulder on said shank adapted to seat on said flanges.

10. In a rotary drill, a drill stem, a ro- 125 tary casing, an expanding drill bit, means on said casing to support said bit, and means to discharge flushing water through both the drill stem and the casing.

11. In a rotary drill, the combination of a

rotatable casing, an inclined supporting flange thereon, a drill stem, a drill collar thereon, a drill bit in said collar, curved arms on the upper end thereof, a conical 5 removable seat in said collar, a conical shank on said bit, and an inclined shoulder on said shank to seat upon said inclined flange on said casing.

In testimony whereof, I hereunto affix my signature this 12 day of Nov., 1918.

ROBERT E. CARMICHAEL,
